CASSETTE TRANSPORT

Orville W. Larson, Elmhurst, Ill., assignor to Ampex Corporation, Redwood City, Calif., a corporation of California

Filed Aug. 18, 1969, Ser. No. 18,724

Term of patent 14 years

Int. Cl. D14—01

U.S. Cl. D26—14

FIG. 1 is a front, top and right side perspective view of a cassette transport, showing my new design; and

FIG. 2 is a bottom, rear and left side perspective view of the transport of FIG. 1.

I claim:

The ornamental design for a cassette transport, substantially as shown and described.
